(57) **CLAIM**

The ornamental design for a table, as shown and described.

DESCRIPTION

FIG. 1 is a perspective view of a table showing our new design;

FIG. 2 is a front view thereof, the back view being identical; FIG. 3 is a right side view thereof, the left side view being identical;

FIG. 4 is a top view thereof;

FIG. 5 is a bottom view thereof;

FIG. 6 is a perspective view of the table of FIG. 1 in an alternative position;

FIG. 7 is a front view of FIG. 6, the back view being identical; FIG. 8 is a right side view of FIG. 6, the left side view being identical;

FIG. 9 is a top view of FIG. 6; and,

FIG. 10 is a bottom view of FIG. 6.

The broken lines illustrating portions of the table form no part of the claimed design.

1 Claim, 10 Drawing Sheets
